(57) **CLAIM**

The ornamental design for a personal care appliance as shown and described.

DESCRIPTION

FIG. 1 is a top perspective view of a personal care appliance showing my new design;

FIG. 2 is a bottom perspective view thereof;

FIG. 3 is a side elevation view thereof;

FIG. 4 is another side elevation view thereof;

FIG. 5 is yet another side elevation view thereof;

FIG. 6 is still another side elevation view thereof;

FIG. 7 is a top plan view thereof; and,

FIG. 8 is a bottom plan view thereof.

The dashed lines in the figures illustrate portions of the design that form no part of the claimed design.

The broken away symbols in the drawings indicate that any portions of the article beyond what is shown forms no part of the claimed design.
